SUCTION DISK PLOW

Clarence E. Newkirk, Orange, Calif.

Application October 10, 1940, Serial No. 360,667

8 Claims. (Cl. 97—53)

This invention relates to improvements in suction disk plows and more particularly to an improved agricultural machine of this character wherein spaced sets of plow disks are arranged at each end of a frame and means are employed for controlling both sets of discs simultaneously.

Another object of the invention is to provide for controlling both sets of disks simultaneously. a suction disk plow wherein the raising means for the sets of suction disks includes an hydraulic jack so that power from the tractor or other prime mover will not be necessary to raise or lower the disks.

A further object of the invention is to provide an improved suction disk plow including improved and highly efficient bearings for supporting the wheels employed.

As a still further object, the invention seeks to provide an agricultural machine of this character, the sets of suction disks of which are arranged in offset relation to said frame.

Another object of the invention is to provide a suction disk plow wherein means are employed for permitting the installation of other devices in lieu of or in addition to the suction disks.

Another object of the invention is to provide a suction disk plow employing improved automatic lifting mechanism which will operate when the machine traverses a right hand turn.

Other and incidental objects of the invention not pointed out hereinabove will become apparent as the description proceeds.

My improved suction disk plow is illustrated in the accompanying drawings, wherein:

Figure 1 is a top plan view of the machine.

Figure 2 is a side elevation showing the lifting wheels in retracted position and the plow disks engaged with the earth.

Figure 3 is a detail perspective view showing particularly the lifting mechanism.

Figure 4 is an enlarged detail perspective view, partly in section, showing one of the improved bearing supports for the wheels.

Figure 5 is a vertical sectional view showing the improved suction disc mounting.

Referring now to the drawings in more detail, it being understood that similar numerals of reference are employed to designate like parts throughout the various views, the numeral 1 indicates, in general, the frame of my improved suction disk plow. The frame includes substantially H-shaped channel side members 2 and 3. It is to be noted that the side member 2 is considerably shorter than the side member 3 with the result that a set of suction disks, to be de-

scribed in more detail hereinafter, will be disposed obliquely at the rear of the frame. At their corresponding forward ends, said members 2 and 3 are connected by an L-shaped front cross member 4. The L-shaped member 4 is of slightly less height than the members 2 and 3 so that the opposite end portion of said L-shaped member will be fitted into the ends of said members 2 and 3. The frame 1 is further provided with a relatively small L-shaped cross member 5 disposed in parallel spaced relation to the member 4 and serves as a support for structure to be described hereinafter.

In order to raise and lower the frame, I provide wheels 6, 7 and 7^a which are mounted on the outer end portions of axles 8. The axles are each of one-piece construction and each include crank portions 9 and 10 and a central portion 11. In Figure 3 of the drawings, the construction and mounting of the lifting mechanism may be seen clearly. It will be noted, by referring to this figure, that the centrally disposed axle 8 is provided, substantially medially of the width of the central portion thereof, with a lever 12 which is normally substantially vertically disposed. The crank axles on opposite sides of the central crank axle 8 are provided with vertical levers 12a, the upper ends of which are pivotally connected to a horizontal connecting bar, the latter being operatively connected with the lever 12 of the central crank axle so that when the lever 12 is actuated to turn said central crank axle, a corresponding turning movement will be imparted to the other crank axles. In order to support the axles 8 adjustably, I provide improved bearings, one of which is shown in detail in Figure 4 of the drawings. The bearings are shown at 13 and are carried at each side of the frame and support the axle at points adjacent the crank portions 9 and 10 thereof. The bearings are identical in every detail and it is accordingly thought that a description of one will suffice for both. With this in view, a typical bearing includes opposed supporting plates 14 and 15 formed with longitudinal slots 16 and 17 which are disposed in longitudinal alignment. Also, aligned openings 18 and 19 are formed in the plates 14 and 15, respectively. A bearing member is adjustably mounted between the plates 14 and 15. The bearing member is shown at 20 and includes a U-shaped plate 21 and a bearing loop 22 bolted or otherwise suitably secured to the U-shaped plate 21. In order to secure the plate 21 to the plates 14 and 15, I employ bolts 23 which pass through the slots 16 and 17 and the openings 18 and 19. It will

be understood that, as bearings 13 are carried on each of the side members 2 and 3, in transverse aligned position, the axle 8 will be effectively mounted on the frame. It will also be understood that by shifting the central axle 8, the wheel thereon may be engaged with the ground for raising one side of the device. If the other axles 8 are shifted for engaging the wheels 7 and 7^a with the ground, the opposite side of the device will be elevated from the ground. The axles carrying the wheels 7 and 7^a are operatively connected with each other by means of levers 12^a and 12^b and a connecting link 12^c.

My improved suction disk plow includes sub-frames 24 and 25. The sub-frame 24 is mounted at the forward end of the frame and is, as will be seen, located obliquely with respect to said frame. Moreover, the sub-frame 24 is offset to the left of the frame, as seen in Figure 1 of the drawings. That is to say, the sub-frame 24 projects obliquely past the side member 2 of the frame 1. The sub-frame 25 connects the side members 2 and 3 at the rear end of the frame 1. The sub-frame 25 is also obliquely mounted and is offset to the right of the frame 1, as seen in Figure 1. In other words, the sub-frame extends to the right past the side member 3 of the frame 1. Moreover, the sub-frames 24 and 25 are both disposed to extend obliquely rearwardly on the frame 1.

In order to effect a plowing operation, plow disks are employed. A set of such plow disks 26 are carried on the sub-frame 24 while a like set of disks 27 are carried on the sub-frame 25. The disks are identical in every respect and, as will be seen, are arranged with their hubs in substantial alinement. The disks 26, however, have their concave faces disposed toward the right while the disks 27 are disposed with their concave faces toward the left. It has been found that this arrangement permits a highly efficient plowing operation. Reference is had to Figure 5 of the drawings wherein it will be seen that each of the disks is held on its sub-frame by means of spring coil shanks 28 which have straight portions 29 secured to the end faces of the sub-frames 24 and 25 by U-bolts 30. The ends of the straight portions 29 are turned up at 31 to provide stops for limiting the shanks 28 against outward displacement. Each of the sets of disks 26 and 27 is provided with a hub assembly 32 securing the disks operatively to the shank 28. The hub assembly includes a hub 33 and a hollow socket 34 which receives the turned down end portion 35 of each of the shanks 28. The disks are thus provided with a spring mounting.

Reference is again had particularly to Figure 3 of the drawings. The relatively small L-iron cross member 5 provides a support for an inverted substantially U-shaped jack mounting standard 36 which has its lower free end portion secured to the horizontal portion of the member 5. Near its upper end a bracket 37 is mounted, which bracket is substantially U-shaped and straddles the upper portion of said standard 36. The bracket 37 is secured to one end of a jack cylinder 38 which is of the fluid operated type. The jack cylinder includes a valve 39 which controls fluid pressure in the cylinder. The valve is to be operated by a lever 40 of L-shape which has its lower end pivoted to the cylinder, as shown at 41. A spring 42 normally retains the lever 40 in retracted position while a cable 43 is attached to the upper end of said lever and permits manual shifting thereof against the tension

of the spring 42 for effecting operation of the valve. Fluid connections to a suitable source of fluid supply are, of course, provided and are shown at 44. The jack cylinder 38 includes a piston rod 45 which is, of course, connected to the piston within the jack cylinder and extends rearwardly medially of the width of the frame and is connected with an adjusting sleeve 46 having handles 47 thereon for manual engagement. The adjusting sleeve 46 has screwed therein a threaded shank 48 provided with a yoke 49 pivotally connected with the upper end of the lever 42. In order to brace the standard 36 I provide diagonally disposed bracing straps 50 and 51 which extend from the bearing structures 13 to points substantially medially of the height of the standard 36 on opposite sides thereof. An inverted U-shaped connecting brace 52 connects the diagonal straps 50 and 51 medially of their length. The brace 52 may have secured thereto the opposite terminal of the spring 42, or, as shown, said opposite terminal may be connected to the jack cylinder. When fluid pressure is introduced to the jack cylinder by the closing of the valve 39, the piston therein will be shifted for shifting the piston rod 45 and causing the lever 42 to be shifted for rocking the crank portions 9 and 10 of the axle 8 and engaging the wheels 6 and 7 with the ground, whereby the plow disk assemblies will be raised from the ground to inoperative position. Of course, when the piston rod 45 is moved in the opposite direction for releasing the fluid from the jack cylinder, the lever 42 will be shifted for causing the wheels to assume the position shown in Figure 2 of the drawings. That is to say, the wheels will be raised and the plow disks 26 and 27 engaged with the earth for a plowing operation. Rotation of the adjusting sleeve 46 will effect such fine adjustment as is necessary to cause the wheels to assume the proper advanced and retracted positions. The wheels 6 and 7 will, of course, effect the raising of the central portion of the frame and the rear portion thereof, together with the sub-frame 25 and the plow disks 27 connected therewith.

In order to raise the forward end of the frame more effectively and insure complete clearance of the plow disks from the earth, I provide additional lifting mechanism which includes a hitching frame 53. The hitching frame comprises a transverse member 54 which is of H-shape channel iron and is connected with the forward end of the frame 1 by side plates 55 and 56. The hitching frame straddles the forward end of the frame 1 with the side plates 55 and 56 lying against, respectively, the depending bearing plates 57 and 58. Pivot bolts 59 and 60 effectively swingingly connect the hitching frame with the main frame 1. A hitching bar of obtuse angular formation is shown at 61. The hitching bar has an inner end portion 62 which engages about the inner edge of the lowermost horizontal portion of the channel member 54. A plurality of openings are formed in the channel member 54 along its length so that the hitching bar 61 may be adjusted to various positions along the length of said channel member. It will, therefore, be possible for the bar to be mounted for right or left hand offset draft. The forward end of the hitching bar is to be connected to appropriate hitching connections on a tractor.

The front end lifting mechanism also includes a mounting yoke 63 which comprises L-shaped members 64 and 65 located in parallel spaced re-

lation to each other and having their corresponding lower ends connected to the substantial mid-portion of the front cross member 4. The yoke 63 pivotally mounts a crank or lever 66 one end of which is connected with a yoke 67 on the hitching frame 53 by means of a link 68. An operating rod 69 connects the opposite end of the crank 66 with the lever 12. Sleeves 10 and 11 are employed for effecting pivotal connection between the rod 69 and the lever 12 and the forward end of said rod 69 and the crank 66 respectively. As will be noted, the sleeve 10 is connected to the lever 12 substantially medially of its height. It will further be noted that the rod 69 extends between the vertical legs of the standard 36 and in vertical alinement with the piston rod 45 and the jack cylinder 38. Braces 12 and 13 connect the cross member 5 with the upper end portion of the yoke 63 for effecting bracing thereof.

It is believed that the operation of the invention will be understood from the foregoing description. A brief description, however, of the operation thereof will follow hereinafter so that a complete understanding of the invention will be assured.

My improved suction disk plow is connected to a tractor by means of the hitching bar 61. The hitching bar is so positioned along the transverse member 54 that the machine will follow directly behind the tractor or will be offset to the left or to the right with respect thereto. In order to permit the machine to be moved from place to place, it is necessary that the wheels 6 and 7 be engaged with the ground and the plow disks cleared therefrom. To accomplish this, the valve 39 is opened for admitting fluid pressure into the jack cylinder 38, when the piston rod 45 will be shifted rearwardly and the lever 12 rocked for shifting the wheels 6 and 7 to the position shown in Figure 3 of the drawings. In this position, the machine may be moved from place to place with facility. After my improved suction disk plow has been placed in a field or orchard to be cultivated and it is desired to lower the wheels, the valve 39 is released by releasing pressure on the lever 40, when fluid flow will enter the rear end of the cylinder 38 and cause the piston rod 45 to be drawn forwardly for rocking the lever 12 forwardly and positioning the wheels as shown in Figure 2 of the drawings. In this position, the plow disks on the sub-frames will be engaged with the earth and will effect a plowing or harrowing operation as the machine is drawn forwardly over the earth. It should be understood that operation of the jack cylinder, with consequent shifting of the piston rod 45 and the lever 12, will effect shifting of the rod 69 which will shift the lever 66 and the link 68. As will now be understood, shifting of the rod 69 by the lever 12, when said lever is being moved to the position shown in Figure 3 of the drawings, will shift the lever 66 and the link 68 so that the hitching structure 53 will be swung downwardly with respect to the rear of the tractor. The result of this swinging movement will be that the sub-frame 24 will be shifted upwardly for disengaging the disks thereon from the earth. When the lever 12 is shifted forwardly, the rod 69 will also be shifted forwardly and the hitching structure 53 will be shifted upwardly for allowing the forward end of the frame to shift downwardly for engaging the disks on the sub-frame 24 with the earth.

The sleeves 10 and 11, together with the adjusting sleeve 46 and the bearing structures 13,

will permit adjustment of the wheels, hitching structure operating mechanism, and piston rod, so that these parts will cooperate to insure raising and lowering of the frame in the proper manner.

It is believed that the construction and operation of my improved suction disk plow will now be understood.

Having thus described the invention, what I claim is:

1. In a suction disk plow, a frame having side members, a front cross member connecting the side members at their forward ends, one of said side members being longer than the other, a sub-frame carried at the rear of the frame and mounted on said frame in oblique relation thereto, disks carried by the sub-frame, a sub-frame carried at the forward end of the frame in oblique relation thereto and having disks thereon, an axle mounted on the frame medially of the length thereof and having a crank portion, a wheel carried by the crank portion, bearings shiftably connecting the axle with the frame, a lever carried by the axle, a standard carried by the frame near its forward end, a jack cylinder carried by the standard, a piston rod carried by the jack cylinder and connected with the lever, and means carried by the jack cylinder and operable for controlling fluid flow to said jack cylinder, said jack cylinder being operable for shifting the piston rod whereby the axle, lever and crank portion will be shifted for rocking the axle and moving the wheel to operative or inoperative position for raising or lowering the frame and the disks thereon out of or into operative position.
2. In a suction disk plow, in combination with a tractor hitch, a frame, plow disks carried by the frame at its opposite ends, means for raising the frame at its mid and rear portions for freeing certain of the disks from the earth in inoperative position, and means cooperating with said first mentioned means and the tractor hitch for raising the forward end of the frame and certain other of said disks to inoperative position, said last mentioned means including a piston rod and a jack cylinder.
3. In a suction disk plow, a frame comprising side members connected by a front cross member, a hitching frame connected with the first mentioned frame, an axle carried by the first mentioned frame and having a crank, a supporting wheel carried by the axle at the free end of the crank, an L-iron cross member carried by the frame, a standard carried by the cross member, a jack cylinder carried by the standard and having a piston rod, a lever carried by the axle, means adjustably connecting the lever with the piston rod, means shiftably connecting the lever with the hitching frame, and means for controlling fluid flow to the jack cylinder, said piston rod being operable by the jack cylinder for shifting the axle and the hitching frame for raising and lowering the front and rear end portions of the frame with respect to a surface therebeneath.
4. In a suction disk plow, a frame having side members and a front cross member connecting said side members at their forward ends, bearing plates carried by the side members at their corresponding forward ends, a hitching frame including side plates and a transverse channel member, means swingingly connecting the bearing plates with the side plates, an axle carried by the frame, a wheel carried thereby, means for shifting the axle for lowering the wheel for raising the central and rear portions of the frame, and means con-

nected with said last mentioned means and said hitching frame and movable with said last mentioned means for shifting the hitching frame simultaneously with movement of the axle whereby the hitching frame will be shifted downwardly for raising the forward end of the frame.

5. In a suction disk plow, a frame having side members and a forward cross member, a hitching frame swingingly connected with the frame and having a hitching bar, a yoke carried by the hitching frame, a mounting yoke carried by the first mentioned frame, a crank carried by the mounting yoke, a link connecting the crank with the first mentioned yoke, an axle carried by the frame, a wheel carried by the axle, said axle having a lever, an actuating rod connecting the lever with the crank, a standard carried by the frame, a jack cylinder carried by the standard, a piston rod carried by the jack cylinder, means adjustably connecting the piston rod with the lever, fluid connections for the jack cylinder, and a valve for controlling fluid flow to the jack cylinder, said jack cylinder being operable for shifting the piston rod and the lever for lowering the wheel and raising the rear and central portions of the frame, said actuating rod, crank and link being simultaneously movable by the lever for urging the hitching frame in a downward direction when the hitching bar is connected with a tractor whereby the forward end of the frame will be raised.

6. In a suction disk plow, a frame having side members and a front cross member, bearing plates carried by the side members, a hitching frame swingingly connected with the first mentioned frame and having side plates, bolts pivotally connecting the hitching frame with the first mentioned frame, said hitching frame including a hitching bar and a transverse channel member, a yoke carried by the channel member, a mounting yoke carried by the first mentioned frame on the front cross member, a crank carried by the mounting yoke, a link connecting the crank with the yoke and the hitching frame, an L-iron cross member carried by the first mentioned frame rearwardly of the front cross member, a standard carried by the L-iron cross member, an axle having a crank portion, a wheel carried by the axle, said axle having a lever, bearings adjustably connecting the axle with the frame medially of its length, a bracket carried by the standard, a jack cylinder carried by the bracket and extending rearwardly of the frame, fluid connections for the jack cylinder, a piston rod carried by the jack cylinder, a threaded shank carrier by the lever, an adjusting sleeve carried by the piston rod and engageable with the threaded shank, an actuating rod connecting the lever with the crank, a

valve carried by the jack cylinder, a valve operating lever carried by the jack cylinder and movable for introducing fluid to the jack cylinder when the piston rod will be shifted for rocking the axle lever and engaging the wheels with a supporting surface for raising the rear and central portions of the frame, said actuating rod being movable simultaneously with the axle lever for shifting the crank and the link and urging 10 the hitching frame downwardly against the obstruction of a support for lifting the forward end of the frame, sub-frames carried by the first mentioned frame, and plows carried by the sub-frames and being movable into and out of plowing position by lowering or raising of the first mentioned frame.

7. In a suction disk plow, a frame, a hitching frame swingingly connected therewith and having a hitching bar adapted for connection with a tractor, a mounting yoke carried by the first mentioned frame, a crank pivotally mounted in the mounting yoke, a link connecting the crank with the hitching frame, an L-iron cross member carried by the first mentioned frame rearwardly of the mounting yoke, a standard carried by the cross member, a jack cylinder carried by the standard, an axle carried by the first mentioned frame, bearings mounting the axle on said first mentioned frame, said axle having a lever, means operatively connecting the jack cylinder with the lever, an actuating rod connecting the lever with the crank, said jack cylinder being operable for shifting said last mentioned means whereby the lever will be shifted for controlling movement of 30 the axle and thus movement of the central and rear portions of the first mentioned frame toward or away from a supporting surface, said actuating rod, crank and link being simultaneously movable for shifting the hitching frame with respect to the first mentioned frame and a tractor connected with said hitching frame so that the forward end of the frame will be simultaneously moved toward or away from said supporting surface, and plows carried by the first mentioned 40 frame and being movable into and out of operative position by movement of the frame.

8. In a suction disk plow, a frame, plows carried by the frame at its opposite ends, a hydraulic jack for raising the frame at its mid and rear portions for freeing certain of the plows from the earth in inoperative position, hitch mechanism, and means connected with said hitch mechanism and cooperating with said jack and a tractor hitch structure for raising the forward end of the frame and certain other of said plows to inoperative position.

CLARENCE E. NEWKIRK.
